UNITED STATES PATENT OFFICE.

JOSEPH C. DONNELLY, OF BARBERTON, OHIO, ASSIGNOR TO THE DIAMOND MATCH COMPANY, OF CHICAGO, ILLINOIS, A CORPORATION OF ILLINOIS.

MACHINE FOR PACKING MATCH-BOOKS, &c.

1,217,923.

Specification of Letters Patent. Patented Mar. 6, 1917.

Application filed June 3, 1916. Serial No. 101,473.

To all whom it may concern:

Be it known that I, JOSEPH C. DONNELLY, a citizen of the United States, and resident of Barberton, in the county of Summit and 5 State of Ohio, have invented certain new and useful Improvements in Machines for Packing Match-Books, &c., of which the following is a specification.

This invention relates to machines for 10 packing match books and the like; having reference more especially to certain improvements in the assembling mechanism of the packing machine set out in Letters Patent of the United States No. 1,132,309, dated March 15 1915. The packing machine forming the subject of said Letters Patent is therein represented as associated with a match-book making machine of the character illustrated in Letters Patent of the United States No. 20 1,042,472, said packing machine being adapted to receive the books as rapidly as they are produced, and through the instrumentality of assembling mechanism arrange them uniformly and compactly side by side 25 with the adjacent books oppositely-disposed relatively to the heads of the matches.

The object of the present invention is to 30 simplify and otherwise improve the construction and operation of the mechanism for positioning the match-books and assembling them in a row or column with the larger ends of alternate books reversed. Accordingly my invention comprises various 35 features of construction and combinations of parts which will be hereinafter described and claimed.

In the drawings—

Figure 1 is an end elevation of a part of 40 a packing machine embodying my improvements, a portion of the match-book making machine being shown.

Fig. 2 is a plan of Fig. 1.

Fig. 3 is a partial view of the mechanism indicated in the lower right-hand corner of 45 Fig. 2; showing the parts in the positions which they occupy at the completion of the operation of inserting the books in the book carrier chain.

Fig. 4 is a rear elevation of the match- 50 packing mechanism shown in Figs. 1 and 2.

Fig. 5 is a vertical section, enlarged, on a plane through the longer trackway, as on the line 5—5 of Fig. 2, showing the book-

reversing turret, the book-carrier, and adjuncts.

55

Fig. 6 is a detail of the Geneva stop motion for actuating the turret and other parts.

Referring to the drawings, 10 designates the intermittently-rotatable pocked wheel of a book-match machine from which the 60 match books are discharged in pairs, headed ends rearward, upon a yielding supporting 65 plate 11 by the action of a reciprocating ejecting frame 12; and 13 designates reciprocating fingers by means of which the free ends of the cover flaps of the books are tucked under the stapled folds of the covers. When the tucking operation has been completed, and the fingers leave the finished books (14), the latter are simultaneously 70 pushed rearwardly, abreast, by the next succeeding pair of books, and so on.

The supporting frame of the packing machine comprises a base 15, standards 16 and table 17. The main drive shaft 18 of 75 the packing machine has its bearings in suitable boxes on the supporting frame, and is operatively geared with the main shaft 19 of the match-book machine. In the present instance the shafts 18, 19 are provided with 80 sprocket wheels 20, 21 respectively, which are connected by a chain 22. The shaft 18 is equipped with a suitable clutch 23 whereby the wheel may be rendered fast or loose on the shaft, as desired. (See Figs. 1 85 and 4.)

The intermittently-movable endless carrier 24 which is herein illustrated as the holder in which the books are assembled in a row or column, comprises a chain of plate 90 links provided on their outer sides with a succession of blades or jaws 25 into the succeeding spaces of which the books, alternately reversed as to their heads, are inserted and thereby held in close relation to each 95 other; such books thus positioned being transported by the carrier to the discharging station. The inner sides of the links are provided with rack-teeth 26 with which meshes the intermittent drive gearing; one 100 of the wheels of which is indicated at 27, Fig. 4.

At the receiving end of the packing machine are vertically-spaced sprocket wheels 28 for the support and guidance of the 105 chain; the studs 29 of said wheels being

borne by a suitable bracket 30 on the table 17. This bracket also provides one of the bearings for an intermittently-actuated shaft 31, the other bearing of which is in a 5 bracket 32 on the table. This shaft 31 carries the gear wheel 27 for impelling the chain.

33, 34 designate two trackways along which the books are fed when they are discharged from the match-book machine; one of these trackways being longer than the other as described in Patent No. 1,132,309 aforesaid. These trackways are formed on a frame 35 which is supported on the table 17, 10 said trackways being slightly inclined as indicated. The lower end of the longer trackway 34 is thus on a somewhat lower level than its companion, as will presently appear. In the present instance the books are advanced along the two trackways by intermittently-movable endless conveyor chains 36, 37, respectively, having regularly spaced lugs 38 which take against the opposing edges of the individual books; the floors of 15 the track-ways being appropriately slotted for the free passage of the chains. These chains are supported by suitably-located sprocket wheels 39, 40 fast on shafts 41, 42 at or near the ends of the respective track-ways. The shaft 42 at the inner end of the 20 longer trackway bears a gear wheel 43 in mesh with a gear wheel 44 on a shaft 45 having its bearings in suitable brackets 46 on the table 17, whereby when said shaft 45 is actuated the motion is transmitted therefrom concurrently to the two conveyor chains 36, 37. The preferred means for actuating the shaft 45 will be hereinafter described.

40 A book-reversing turret 47 is mounted to turn in the space between the delivery end of the short trackway 33 and the receiving end of the book carrier 24. This turret, in its preferred form, comprises a body or disk 45 affixed to one end of an intermittently rotatable shaft 48 having its bearings in brackets 49 on the table. On the inner face of the disk are four equally-spaced radial book-holders, each of which in the present 50 instance is in the form of a clip. This clip comprises a fixed jaw 50 formed on or secured to the disk, and a yielding complementary jaw 51 which is preferably composed of spring metal. The body of the metal extends laterally of and in spaced relation to the fixed jaw and its lower end is bent and secured to a lug on the fixed jaw. The outer end of the yielding jaw 51 is flared outwardly, as at 52, in order that a book may 55 be readily pushed endwise into the space between the jaws of the clip and be therein yieldingly clamped.

The shaft 48 is intermittently actuated in such a manner as to present the suc-

sive clips of the turret horizontally to the delivery end of the short trackway, and similarly to a book-receiving space of the book carrier 24, each book being endwise reversed as it is conveyed by the turret from the receiving to the discharging position; that is to say, at each dwell of the turret 47 one of the clips is positioned to receive a match-book from the short trackway, and the diametrically-opposite clip is positioned adjacent the book-carrier in order that a book previously entered in the latter clip and endwise reversed may be transferred to the carrier, as seen most clearly in Fig. 5. A segmental plate 47' is preferably arranged to overhang the path of the clips during a part of their travel from the receiving position, and thus serve as a cam for the opposing edges of projecting books to insure their complete entry into the successive clips before they reach the discharging position. 85

The shaft 48 is preferably actuated by a Geneva stop motion; the radially slotted driven member 53 of which is affixed to the shaft, while the complementary pin drive and locking members 54 are loosely mounted on a stud 55 which is supported by the bracket 49. The hub of the pin drive member is provided with a sprocket wheel 56 which is connected by means of a chain 57 with a sprocket wheel 58 on a counter shaft 59 having its bearings in depending brackets 60 beneath the table. This counter-shaft is provided with a gear wheel 61 which is driven from a gear wheel 62 on the main shaft 18 through an interposed idler gear 63. By this construction the counter-shaft is positively driven from the main shaft, and the motion is transmitted through the Geneva stop in a manner to rotate the turret shaft 48 intermittently and temporarily 100 lock it at the end of each impulse.

The turret shaft is provided with a gear wheel 64 in mesh with an idler gear 64' which in turn meshes with a gear wheel 65 on the chain driving shaft 45; thereby effecting concurrent operation of the two shafts. (See Figs. 2 and 4.) 110

When the turret is at rest the proximate match book on the shorter trackway is transferred from the latter to the opposing clip 115 and the match-book in the opposite clip is ejected from the latter and transferred to the opposing receiving portion of the carrier. The preferred means for introducing the books to the clips successively presented thereto includes a vibratory dog 66 which is movable toward and from the axis of the turret, said dog in its outer stroke riding upon the top of the underlying book and then dropping to position against the narrow edge of the book, and in its return stroke pushing the book bodily into the opposing clip of the turret. The dog 66 is 120 125

carried by the free upper end of a rocker arm 67 which is pivoted at its lower end to a bracket 68 on the supporting frame. The arm is pivotally connected by means of a 5 pitman 69 with an eccentric 70 on the main shaft 18, whereby during the operation of the packing machine the said rocker-arm and the dog carried thereby are positively actuated.

10 The preferred means for ejecting the inverted books from the successive clips of the turret and entering them in the spaces between the blades of the carrier 24 includes a finger 71 which is movable toward and 15 from the carrier in a path intersecting the plane of the opposing book, said finger in its outer stroke impinging against the larger end of the book and forcing it from the clip into the carrier and then returning it to its 20 normal position for a similar action on a succeeding book. In the present instance the finger is formed on or secured to the free upper end of the longer arm 72 of a lever which is pivoted to a depending bracket 73 on the table. The shorter arm 25 74 of this lever bears a roll 75 which runs in the groove of a face cam 76 on the counter-shaft 59; the contour of the cam groove being such as to effect the timely actuation 30 of the lever.

The longer trackway 34 extends somewhat beyond the carrier, and the chain 37 therein is of sufficient length to deliver the books to the outer end portion 34' of the trackway. This portion is on a plane somewhat below the axis of the turret and its side walls are longitudinally open or slotted, for the free passage of an angular head 77 to the embrace of which the books are successively delivered by the chain 37. This head 40 is formed on or secured to a horizontal supporting member 78 which in the present instance is of angular form. This member is equipped with spaced pins 79 which depend 45 through corresponding arcuate cam slots 80 in the frame 35, whereby when said member is bodily moved longitudinally of the trackway the former and its head 77 are guided through an arc which intersects the trackway. The path of the head is such that the book embraced thereby is pushed sidewise through the inner open or slotted side wall of the trackway, is swung with its narrow 50 edge toward the outer side of the carrier 24, and is entered into the opposing book-receiving space of the latter, such book thus being in a reverse position to the adjacent book transferred to the carrier from the turret.

60 A simple and efficient means for actuating the member 78 is as follows: One of the depending pins is connected with a rock arm 81 which is pivoted on the under side of the frame 35. The pivot stud 82 of this

arm bears a crank 83 which is connected by 65 means of a link 84 with a similar crank 85 on a vertical rock-shaft 86. This shaft is provided at its lower end with a crank arm 87 carrying a roll 88 which projects into the peripheral groove of a cam 89 on the 70 counter-shaft 59. The contour of the cam groove is such as to impart the timely oscillatory movement to the crank-arm 87, and thus through the described crank and link connections transmit the requisite movement to the member 78 and its book-shifting head 77.

The co-operative relation of the above-described mechanisms for inserting the books into the carrier from the respective sides 80 of the latter is such that the oppositely-disposed books are simultaneously inserted into the adjoining book-receiving spaces of the carrier by means of the finger 71 and the head 77 respectively. At the same time 85 a match-book is transferred from the short trackway to the turret by the action of the dog 66. During such inserting operation the turret 47, the carrier 24 and the feeding chains 36, 37 are at rest. During the return movement of the dog 66, the finger 71 and the head 77 return to their original positions; the turret is moved a quarter-turn to present an empty clip to the plane of the short trackway and a filled clip to 90 the plane of the receiving portion of the carrier; the carrier is advanced to bring a pair of spaces to position for the reception of the next succeeding oppositely-disposed match-books; and the feed chains are simultaneously moved to advance match-books to 95 the lower discharging portions of the short and long trackways respectively preparatory to their transference to the turret and carrier respectively.

100 It is to be understood that my invention is not limited to the particular construction herein shown and described, as the mechanism may be variously modified and be within the scope of the appended claims.

105 I claim—

1. In a machine for assembling match books and the like, the combination of a support for the articles, means for impelling said articles in flat position in adjacent rows along said support, means for reversing the articles of one row, an article holder, means for inserting the articles thus reversed into said holder, and means for shifting the successive books flatwise and unreversed from the other row and inserting them in that position into the holder.

115 2. In a machine for assembling match books and the like, the combination of a support for the articles, means for impelling said articles in flat position in adjacent rows along said support, means for reversing the articles of one row, an article holder,

means for inserting the articles thus reversed into said holder, and means for shifting the successive books flatwise and unreversed from the other row and inserting them in that position into the holder simultaneously with the insertion of the reversed books.

3. In a machine for assembling match-books, and the like, the combination of a support for the articles, means for impelling said articles in flat position in adjacent rows along said support, means for reversing the articles of one row, a carrier having article receiving portions arranged to travel adjacent the path of the reversed books, means for inserting the reversed books successively into the receiving portions of the carrier presented thereto, and means for shifting the successive books flatwise and unreversed from the other row and inserting them in that position into receiving portions of the carrier presented thereto.

4. In a machine for assembling match-books, and the like, the combination of a support for the articles, means for impelling said articles in flat position in adjacent rows along said support, means for reversing the articles of one row, a carrier having article receiving portions arranged to travel adjacent the path of the reversed books, means for inserting the reversed books successively into the receiving portions of the carrier presented thereto, and means for shifting the successive books flatwise and unreversed from the other row and inserting them in that position into the receiving portions of the carrier presented thereto simultaneously with the insertion of the reversed books.

5. In a machine for assembling match books and the like, the combination of a support for the articles, means for impelling said articles in flat position in adjacent rows along said support, a rotary element having individual article holders in spaced relation to each other, means for actuating said element whereby the holders thereof are presented at intervals to diametrically-opposite receiving and discharging regions, a carrier arranged to travel adjacent the discharging region, means for inserting successive articles of one row into the holders at the receiving region, whereby said articles are endwise reversed when they are carried to the discharging region, means for placing the reversed articles on the carrier, and means for shifting the successive articles flatwise and unreversed from the other row and placing them in that position on the carrier.

6. In a machine for assembling match books and the like, the combination of a support for the articles, means for impelling said articles in flat position in adjacent rows along said support, a rotary element having individual article holders in spaced relation

to each other, means for actuating said element whereby the holders thereof are presented at intervals to diametrically-opposite receiving and discharging regions, a carrier arranged to travel adjacent the discharging region, means for inserting successive articles of one row into the holders at the receiving region whereby said articles are endwise reversed when they reach the discharging region, means for placing the reversed articles on the carrier, and means for shifting the successive articles flatwise and unreversed from the other row and placing them in that position on the carrier simultaneously with the reversed books.

7. In a machine for assembling match books and the like, the combination of a support for the articles, means for impelling said articles in adjacent rows along said support, a rotary element having individual article holders in spaced relation to each other, means for actuating said element whereby the holders thereof are brought at intervals to diametrically-opposite receiving and discharging regions, a carrier arranged to travel adjacent the discharging region, means including a vibratory member, for inserting the articles of one row into the holders when they are at the receiving region, means, including a reciprocatory member, for discharging the reversed articles from the holders when they are at the discharging position and inserting said articles into the carrier, and means for shifting the successive articles flatwise and unreversed from the other row and inserting them in that position into the carrier.

8. In a machine for assembling match books and the like, the combination of a support, including two trackways of different lengths, endless conveyers for impelling articles in flat position along the respective trackways, a rotary element having individual article holders in spaced relation to each other, means for actuating said element whereby the holders thereof are brought at intervals into close relation with the discharging end of the shorter trackway and to a diametrically-opposite position, a carrier arranged to travel adjacent the latter position, means for transferring the articles from the shorter trackway to the adjacent holders whereby said articles are in reverse position when they are brought adjacent the carrier, means for transferring the reversed articles from the holders to the carrier, and means for transferring the successive articles flatwise and unreversed from the longer trackway to the carrier.

9. In a machine for assembling match books and the like, the combination of a support for the articles, means for impelling said articles in flat position in adjacent rows along said support, means for endwise re-

versing the succeeding articles of one row, an article holder, means for inserting the articles thus reversed into said holder, means for transferring the successive books from 5 the other row to the holder, the last-named means comprising an article engaging member and guiding and operating mechanism

therefor whereby said member is swung in a path across the adjacent row of books and toward the article holder.

10

Signed at Barberton, in the county of Summit and State of Ohio, this 31st day of May, A. D. 1916.

JOSEPH C. DONNELLY.
